UNITED STATES PATENT OFFICE.

KOBY KOHN, OF NEW YORK, N. Y.

SAFETY TOY TORPEDO.

Application filed March 5, 1928. Serial No. 92,572.

This invention relates to torpedoes and more particularly to toy torpedoes adapted to be exploded by impact.

It is a general object of the present invention to provide a novel and improved type of toy torpedo.

More particularly it is an object of the present invention to provide a novel and improved toy torpedo which is not adapted to 10 explode except upon intentional and violent impact of the torpedo against a hard surface.

Another object of the present invention consists in the provision of a toy torpedo in 15 which there are no loose or movable parts.

Still another object of the present invention consists in the provision of a toy torpedo in which the explosive compound is confined in a frangible container having interior walls slightly spaced apart and adapted to contact with each other when the container is fractured by impact against a hard 20 surface.

A further object of this invention consists 25 in the provision of a toy torpedo provided with a frangible explosive container which is completely surrounded and enclosed by a resilient gastight covering which adheres to the outer surface of the casing.

A still further object of the invention consists 30 in the provision of a toy torpedo which is waterproof and in which the explosive compound cannot be abraded or subjected to percussion without the actual fracturing of a portion of the container or casing.

Another and further object of the present invention consists in the provision of a container 35 for the explosive compound of a toy torpedo, which container has interior walls opposing and spaced apart and covered with an abrasive, certain of said walls being adapted to come into contact with each other upon the fracturing of parts of the container.

Other and further objects of this invention 45 will be more apparent to those skilled in the art by a consideration of the accompanying drawing and following specification wherein are disclosed several exemplary modifications thereof with the understanding, however, that various changes may be made therein by those skilled in the art without departing from the spirit of the invention or the scope of the appended claims.

In said drawing:

Fig. 1 is an elevation of a spherical type of torpedo;

Fig. 2 is a section taken in a plane through the center of the torpedo shown in Figure 1 and axially of the recess therein;

Fig. 3 is a plan view of the torpedo with the outer covering or enclosing casing left off and the cap to the container removed;

Figs. 4, 5 and 6 are views corresponding to Figures 1, 2 and 3 but of a cylindrical type of torpedo;

Fig. 7 discloses a plan and elevation of the container closure cap adapted for use in the modification disclosed in Figures 1, 2 and 3;

Fig. 8 is a perspective view of the container closure cap adapted for use with Figures 4, 5 and 6;

Fig. 9 is a transverse section taken between the ends of the torpedo disclosed in Figure 4 at the instant of impacting the same against a hard surface and showing fractures in the explosive container;

Fig. 10 is a central vertical section through a modified type of cylindrical torpedo;

Fig. 11 is a transverse section of the same on line 11—11 of Figure 10; and

Fig. 12 is a view similar to Figure 11 of another form of torpedo.

In the common type of toy torpedo as now manufactured for use on 4th of July and similar festive occasions, it is usual to form a cylindrical or other suitably shaped shell or casing of paper, cardboard or the like and to place in this shell the explosive composition. The usual explosive for toy torpedoes consists of an intimate mechanical mixture of powdered chlorate of potash, antimony and sulphur in vary proportions, depending upon the desired sensitivity of the explosive. In addition the shell is partially or completely filled with what may be termed the detonating elements, usually small particles of gravel or other sharp granular material.

The shell is then sealed up by a suitable material and is adapted to be exploded by being thrown against a hard object, such as the sidewalk. The impact of the torpedo against the hard surface causes abrasive action between the particles of gravel and between these particles and the walls of the casing, and since in the process of manufacture the torpedoes are tumbled, the powdered compound is scattered through the interstices between the detonating elements, it is thus subject to friction, with its resulting heat,

and percussion which causes the compound to explode. The sudden generation of gases disrupts the casing, producing a loud report.

The present invention has for its object 5 the provision of a torpedo which will overcome substantially all of the hazards attendant upon the manufacture, transportation and storing of torpedoes regardless of the quantity of explosive material used or 10 the carelessness in handling. Before the torpedo can be exploded, it must receive an impact sufficiently hard to actually break or destroy the container or casing in which the explosive is confined. Torpedoes constructed according to the present invention 15 have been repeatedly dropped on hard surfaces and thrown into the air and allowed to fall on sidewalks and the like without explosion. Explosion only results upon throwing the torpedo with great force against a hard surface.

The most important element in the torpedo is the container for the explosive material. While it is not necessary, I prefer to 20 use, for the purpose of constructing this container, the pitch mastic composition as described in my co-pending United States application Serial No. 45,647, filed July 23, 1925. A container formed of such material 25 may be readily molded into any suitable form, is waterproof, and upon explosion breaks into small particles which are insufficient in size and weight to be thrown any appreciable distance by the force of the explosion or to cause any injury to bystanders. 30 The pitch cups, casings or containers may be molded as described in the above mentioned application or in any other suitable manner to produce the form of container illustrated 35 in the accompanying drawing. Whereas in the previous application one of the objects to be attained was to provide a container or cup for the explosive which would not break upon the impact resulting in explosion but which would later break as a 40 result of explosion, this invention contemplates the provision of a container for the explosive which will break upon the necessary impact to cause explosion.

Various forms of containers may be made, 45 but in the present application but two will be described, a spherical one and a cylindrical one.

Referring to Figs. 1, 2 and 3, there is disclosed at 15 a container formed of the aforementioned pitch mastic or other suitable composition. It is generally of spherical shape and provided on its exterior with a plurality of chordal slots or grooves 16 lying in planes which intersect along one axis of the sphere. At one end of the previously mentioned axis a circular depression 17 is provided having a diameter slightly less than the distance between the bottoms of opposite grooves 16. Leading from this de-

pression 17 into the interior of the container are a plurality of connecting grooves or channels 18 likewise lying in planes intersecting on the aforementioned axis. These grooves are shown as co-planar with the exterior grooves although this is not necessary. The grooves all intersect each other along the axis of the sphere and as shown in Fig. 3 form a recess or compartment for the explosive compound which is cruciformed in cross-section and closed at one end. The grooves 18 extend to near the wall of the sphere opposite the depression 17 leaving but a thin wall 19 and they extend to within a short distance of the bottoms of the grooves 16 leaving the thin parallel walls 20 separating the interior and exterior grooves. The exterior grooves are tapered and wider at their tops than at their bottoms. They may likewise be tapered from one end to the other for ease in drawing them from a mold if this is found necessary. It will be seen that the above construction provides a spherical container which is divided into sectors held together 90 only by the thin walls 20 and the thin bottom wall 19 so that upon slight impact these thin walls may be broken, separating the sectors for a purpose to be hereinafter described. In commercial forms of the torpedo the walls 20 are approximately one thirty-second of an inch thick although this thickness is dependent upon several factors, foremost among which is the size of the torpedo.

The walls of the slots 18 are covered with an abrasive material 21 such as sand, emery, ground glass or the like preferably crushed to a size to pass through a forty-mesh sieve. It may be secured to the walls of the slots by means of a pitch solvent, if a pitch container is used; any suitable kind of cement, or by the agency of heat, in which case the abrasive may be heated and applied to the walls or the walls heated to soften the pitch and the abrasive applied thereto. Other means may be used for applying the abrasive, such as causing it to adhere to the walls of the slot at the time of molding or otherwise forming the container. The explosive composition 22 of the type previously described is then introduced into the recess formed by the slots 18 and a seal or cap 23, shown in Figure 7, applied in the recess 17 to retain the explosive in position. This cap or seal may be cemented in place or may be applied hot and thus caused to adhere to the material of the container.

After thus being sealed up, the container may be dipped in or otherwise covered with any suitable gas confining material 24 which entirely surrounds the same and serves as a medium to confine the gas while it is expanding after explosion and to afterward be burst by the force of the explosion.

After thus formed the torpedo is adapted to be exploded upon the receipt of a sufficient impact to fracture the interior container 15. Owing to its construction the 5 weakened walls 20 will be the first to break. The slots 18 are very narrow, approximately .070 of an inch and the coating of abrasive on the walls thereof further reduces the space between these walls. The slots being 10 completely filled with explosive compound, it will be found that upon the tumbling operation attendant upon the manufacture of the torpedoes the impalpable powder forming the explosive will be thoroughly spread 15 over the surface of all of the granules of abrasive material so that upon the cracking of the walls 20 and the bottom wall 19 any slight movement of the thus separated sectors of the container will cause the abrasive 20 covered walls 18 to contact with each other and detonate the explosive material between them.

The complete and intimate contact between the abrasive particles and the explosive compound is a most important feature 25 of the invention for its results in a high degree of efficiency, substantially every torpedo exploding upon sufficient impact.

It is important, in order to maintain the 30 torpedoes as safe as possible, to use an explosive of as low a degree of sensitivity as possible and to increase the probability of explosion by the application of sufficient heat and abrasion at the time of impact. In 35 the common types of torpedoes as now made, this is caused by the gravel, the kinetic energy of the impact being transformed into heat energy and this heat energy, although slight, is sufficient to raise the temperature of the explosive so that it will detonate. The usual type of gravel torpedo contains from 30 to 50 pieces of gravel while in the 40 present type of torpedo there are from 500 to 800 particles of abrasive material, thereby increasing the probability of explosion at least ten times.

In the present torpedo the abrasive elements are stationary and accidental explosion, therefore, cannot result for the movement of the impalpable explosive particles against the abrasive during manufacture and shipping cannot cause sufficient heat to 45 explode the compound and it has been conclusively proven by actual experiments that, regardless of how vigorously the torpedo is shaken or agitated, even when using an explosive of a higher degree of sensitivity than could be used commercially, no explosion 50 will take place. This is of particular value when it is considered that toy torpedoes are mainly used by children who cannot always be taught the proper respect for explosives.

The exterior covering or casing 24 serves 55 to confine momentarily the gases of the explosion and allow them to reach a sufficient

pressure to cause a loud report when this casing is finally ruptured. The casing may be formed of glue or like material which is suitably waterproofed not only to protect the explosive but to prevent the torpedoes 70 from sticking together. Wood fibre, particles of paper, coloring material, etc., may be incorporated in the material of the outer casing to give it added strength and to lend a decorative feature to the torpedo. These 75 colors may well be red, white and blue since the torpedoes are most often used on patriotic occasions. The outer covering must be flexible in order that it will allow of sufficient deformation to cause breaking of the 80 interior container while it remains intact itself. It is highly desirable that this covering shall have the necessary quality to allow it to adhere to some extent to the outer surface of the container. This feature adds to 85 the safety of the torpedo both in manufacturing and in shipping, so that minor shocks or pressures sufficiently great to cause cracking of the walls 20 will not allow the sectors of the container to move together and cause 90 explosion by abrading the explosive compound between the walls of the slots 18. This adhesion, however, will not be sufficiently great to prevent intentional explosion of the torpedo upon a sufficiently hard 95 impact. Experiments have proven that animal glue to which a small quantity of formaldehyde has been added to render the glue waterproof is a satisfactory material for the above purpose.

In Figs. 4, 5 and 6 are disclosed a cylindrical form of torpedo. Its construction is essentially the same as the torpedo disclosed in Figs. 1, 2 and 3 but it will be seen that the exterior cylindrical wall of the explosive container 15' is not slotted, the interior slots 18' extending to within a very short distance of the outer surface of the cylinder and the bottom wall 19' being of about the same thickness as the outer wall 20' adjacent the slots. The upper recess 17' is adapted to receive the disk-like closure cap 23' shown in Fig. 8. The whole explosive container is covered by an exterior casing 24', as in the previously described modification. 105 The walls of the slots 18' are similarly coated with abrasive 21' and the recess filled with explosive compound 22'.

If handled carefully the separate elements of the explosive compound, i. e.; chloride of 110 potash, antimony and sulphur, are not explosive, and for safety in manufacture these elements are separately introduced into each torpedo. This is done by dipping each element of the compound in the form of an 115 impalpable powder from a large container, with an instrument resembling a small spoon and dumping it into the torpedoes individually, or in groups by a multiple instrument. In order to render it easier to 120

introduce the powder, the torpedo may take the form disclosed in Figs. 10 and 11, which resembles Figs. 4, 5 and 6 with the exception of the provision of a substantially semi-spherical recess 25 just below the closure cap 23" which acts like a funnel communicating with the slots 18" which have the abrasive covered walls. This recess or pocket is sufficiently large to receive the necessary ingredients of the explosive, each of which is shown individually at 26, 27 and 28 in Fig. 10, having become compacted into soft lumps by the filling process. When the torpedoes are completed they are tumbled in a suitable rotating drum which causes the elements of explosive compound to be thoroughly mixed and completely spread over the surfaces of the abrasive as previously described. The recess or pocket does not prevent explosion of the torpedoes even if they should be stored in a reversed position or strike in this position when thrown, for a sufficient quantity of the explosive will always adhere to the abrasive and be held in the interstices between the granules thereof to thus insure an explosion when the torpedo is impacted.

Reference to Fig. 9 will disclose the condition at the moment of impacting a torpedo of the type disclosed in Figs. 4, 5 and 6 against a hard surface 30. The torpedo has been indicated as striking upon its side but it has been conclusively demonstrated that the torpedoes will explode no matter at what angle they strike a hard surface. This has been demonstrated by recovering fragments of exploded torpedoes which indicate by marks on their surfaces the exact angle at which they have struck. In Fig. 9 the cracks 29 in the thin walls 20' show how the casing or explosive container has been broken into four sectors which have moved inward toward each other sufficiently to cause contact between the abrasive on opposite walls of the slots 18' and thus explode the compound contained between them. The outer casing 24' is shown as unbroken for it will be recalled that it is sufficiently resilient to undergo considerable distortion before cracking.

It is extremely important that the walls of the torpedo which are intended to be broken upon impact be thin enough to insure cleavage at these points only, so as to thus obtain a clean break without dust or small particles which might mix with the explosive composition and either prevent an explosion or so impair the violence thereof as to render the torpedoes commercially impracticable. The breaking of the thin walls 19 and 20 or 19' and 20' does not cause any appreciable dust as the angles of intersection of the walls of the slots 18 are sufficiently sharp to give maximum cleavage with an almost entire absence of dust. The fact that dust is absent has been established by success-

ful experiments using an explosive of so low a degree of sensitivity as to prevent its explosion were it to be even slightly contaminated.

The introduction of the abrasive on the walls of the slots 18 so narrows them that the amount of movement between the separated sectors to cause them to come together upon impact need be but slight. This feature is of great importance, for the opposing walls thus contact so quickly as to secure the benefits of all of the force of explosion and thus cause maximum friction and impact between the opposing and contacting abrasive walls, thus creating a high degree of heat and permitting the use of an explosive having low sensitivity and thus a high safety factor. By causing the container to break in but a small number of pieces upon the actual impact against a hard surface these pieces are of a maximum weight and thus more effectively create friction upon their contacting with each other. This results in an advantageous condition which allows the use of a smaller amount of explosive in the present type of torpedo than can be used in most of the gravel types in order to secure the same volume of sound and at the same time a larger percentage of perfect explosions.

In the spherical type of torpedo the tapering of the exterior slots 16 not only provides adequate draft for removing the container from the mold but insures freedom of movement of the sectors upon fracture of the walls 20 in spite of the slight adhesion of the exterior coating 24 which usually partially or completely fills these slots 16.

In Fig. 12 there is disclosed a torpedo identical in structure with that disclosed in Figs. 10 and 11 with one exception. The abrasive has been omitted. It has been found that where the material of the container is sufficiently hard excellent results can be obtained without the use of abrasive for, as shown in this figure, the opposing walls of the slots 18³ are quite close together so that an impact in any direction on the exterior of the casing causes the cracking of the thin separating walls 20³ with the result that at least two walls of the slots 18³ will come into contact with each other with sufficient force to cause the explosive 22³ to be detonated. The elimination of the abrasive material considerably cheapens the manufacturing cost of the torpedo and decreases the time necessary to make each one.

To recapitulate, we find that the present improved type of torpedo is, in the first place, absolutely safe; that is, it cannot be exploded except upon intentional and violent impact, due to the fact that all the percussion means are stationary until the explosive container is actually disrupted to

allow normally separated portions thereof to some into engagement with each other. Second, a lesser quantity of explosive may be used to obtain the same violence of explosion. Third, substantially 100% efficiency, by which is meant that the percentage of failures, that is, torpedoes failing to explode upon sufficient impact, is almost zero, due not only to the large number of abrasive particles but to the weight of the sections to which they are secured and to the small distance through which these sections must move. Fourth, a torpedo having a minimum number of parts commensurate with reliable operation. Fifth, ease of manufacture. Sixth, waterproof construction insuring the explosive compound against dampness; and seventh, a pleasing and attractive appearance.

Having thus described the invention what is claimed as new and desired to be secured by Letters Patent is:

1. An explosive container for a toy torpedo having opposing interior surfaces close together and comprising cooperating friction means.

2. An explosive container for a toy torpedo having a closed compartment, facing surface within said compartment, said surfaces having abrasive thereon.

3. An explosive container for a toy torpedo having interior slots and exterior indentations forming thin frangible walls therebetween.

4. A container for explosive for a toy torpedo comprising a frangible mass having a narrow recess therein and a chamber communicating with said recess, said chamber and recess being adapted to receive an explosive.

5. An explosive container for a toy torpedo having interior surfaces defining a compartment for explosive, said surfaces being positioned apart and capable of frictional engagement with each other to ignite said explosive upon rupture of a part of said container.

6. A toy torpedo including in combination an explosive compound, an enclosing mass therefor, said mass having abrasive interior surfaces in contact with said explosive, said surfaces being adapted for engagement with each other to ignite said explosive upon rupture of the mass.

7. An explosive container for a toy torpedo having opposing interior walls relatively close together compared with the dimensions of said torpedo, said walls being abrasive to ignite the explosive.

8. An explosive container for a toy torpedo having opposing interior walls one of said walls being coated with an abrasive.

9. A moulded container for a toy torpedo having a narrow interior groove, the

walls of which are abrasive and adapted to 65 cooperate with each other.

10. A safety toy torpedo comprising a container and an explosive therein, and means for detonating said explosive only upon the contacting of portions of said container with each other.

11. A safety toy torpedo comprising a container and an explosive therein, said explosive being of such a sensitivity as to require abrasion to explode it, and abrasive means 75 stationary in respect to each other except upon breaking of said container.

12. A container for explosive material for a toy torpedo having integral interior abrasive surfaces spaced apart.

13. A safety toy torpedo comprising a container and an explosive therein, said explosive being of such a sensitivity as to require friction to explode it, and friction producing means separated from each other by frangible means, except upon breaking of said container.

14. A container for explosive material for a toy torpedo having stationary interior cooperative friction surfaces spaced apart, and 90 explosive material between said surfaces.

15. In a toy torpedo adapted to be exploded by impact, in combination a container of frangible material having a recess, explosive material in said recess, the walls 95 of said recess being opposing and closely adjacent whereby upon fracture of said container said walls will move toward each other to detonate the explosive.

16. In a toy torpedo adapted to be exploded by impact, in combination a container of frangible material having a recess, explosive material in said recess, the walls of said recess being opposing and closely adjacent whereby upon fracture of said container said walls will move toward and contact with each other to detonate the explosive, and an enclosing envelope of flexible material surrounding said container.

17. In a toy torpedo adapted to be exploded by impact, in combination, a container of frangible material having a recess therein, explosive material in said recess, the walls of said recess being abrasive whereby upon fracture of said container said walls 115 will move toward and contact with each other to detonate said explosive by abrasion.

18. In a toy torpedo adapted to be exploded by impact, in combination, a container of frangible material, an explosive 120 enclosed therein and a flexible covering enclosing said container.

19. In a toy torpedo adapted to be exploded by impact, in combination a container of frangible material, an explosive 125 confined therein and a flexible covering enclosing said container and adhering thereto.

20. In a toy torpedo adapted to be ex-

ploded by impact, in combination a container of frangible material, an explosive enclosed therein and a flexible waterproof covering enclosing said container.

5 21. In a toy torpedo adapted to be exploded by impact, in combination a container of frangible material, an explosive confined therein and a flexible waterproof covering enclosing said container and adhering thereto.

10 22. In a toy torpedo, in combination an explosive container comprising relatively heavy sections joined together by frangible means and an explosive compound between said sections and adapted to be exploded by friction between said parts resulting from impacting said torpedo to break said frangible means.

15 23. In a toy torpedo, in combination an explosive container comprising relatively heavy sections joined together by frangible

means and an explosive compound between said sections and adapted to be exploded by friction between said parts resulting from impacting said torpedo to break said frangible means, and a flexible covering for said container.

25 24. In a toy torpedo adapted to be exploded by impact, in combination a container comprising bitumen, an explosive enclosed therein, and a flexible, gastight covering enclosing said container and adhering thereto.

30 25. A container for explosive for a toy torpedo, comprising a frangible mass having a narrow, open ended recess therein adapted to contain explosive, said recess being enlarged at its open end to aid in loading said container with said explosive.

35 In testimony whereof I hereunto affix my signature.

KOBY KOHN.
